UNITED STATES PATENT OFFICE

RALPH E. SMITH, ROY J. ARNOLD, AND RALPH O. CURFMAN, OF GALION, OHIO, ASSIGNEES TO THE GALION METALLIC VAULT COMPANY, OF GALION, OHIO, A CORPORATION OF OHIO

DUMP BODY

Original application filed May 9, 1927, Serial No. 190,091. Divided and this application filed December 19, 1927. Serial No. 241,080.

Our invention relates to dump bodies and mechanism for operating the dump bodies, and is a division of our application, Serial No. 190,091, filed May 9, 1927.

5 It is the object of our invention to provide an elevating mechanism for dump bodies which will telescope beneath the dump body to economize in space which is flexible, and which will provide a rigid support when in 10 supporting position.

It is our object to provide an articulated dump body support, flexible so far as actuation is concerned and rigid so far as its supporting function is concerned.

15 Referring to the drawings:

Fig. 1 is a side elevation of the vehicle in lowered position.

Fig. 2 is a section on the line 2—2 of Fig. 3.

Fig. 3 is a section on the line 3—3 of Fig. 5.

20 Fig. 4 is a section on the line 4—4 of Fig. 3.

Fig. 5 is a side elevation of the mechanism in elevated position.

Fig. 6 is a top plan view of the flexible elevating element.

25 Fig. 7 is a side elevation thereof.

Fig. 8 is a bottom plan view thereof.

Fig. 9 is a section on the line 9—9 of Fig. 3.

Fig. 10 is a perspective view of a link.

Referring to the drawings in detail, 1 and 20

indicate side rails of a truck frame joined by the transverse member 3. The side frame members are further joined by the transverse member 4. The two transverse members 3 and 4 are joined together by the spaced parallel braces 5 and 6 which are parallel to the side frame members 1 and 2 and spaced therefrom. The side frame member 1 carries a shaft 7 on which is mounted a handle 8. This side shaft 7 actuates a bevel gear 9

40 which in turn actuates a bevel gear 10 mounted on a jack shaft 11. This jack shaft 11 is provided with a worm 12 meshing with the worm gear 13 mounted on the shaft 14 which is journaled at 15 on the side frame 1 at 16

45 on the brace member 5 and at 17 on the brace member 6. The shaft 14 has mounted thereon a pair of spaced sprocket wheels 18 and 19. These sprocket wheels are adapted to travel within a guide housing which is arcuate in shape, designated 20, which carries a yield-

ing chain guide block 20^a, and which has a guiding surface 21. The sprocket wheels are spaced from this guide housing. Between the guide housing and the sprocket wheels and engaging the sprocket wheels is a roller chain 55 constructed as follows. The links consist of a plate portion designated 22 having side walls 23 which project inwardly and forwardly beyond the plate 22 in the form of arms 24, such arms terminating in laterally disposed bearings 25. These bearings do not meet but are spaced apart to provide a space for the rotation of the roller 26 which is mounted on the shaft 27. This shaft 27 passes through the bearings 25 and through the next 60 adjacent side walls 23 and serves as a connecting member for connecting each link to the other. Projections 28 on the sides 23 of the plate 22 provide guards and guiding surfaces to laterally position the chain in trough 70 32. The projections 28 extend from the sides of the links and serve to properly position the chain as it passes through the trough 32. By this means the other parts of the links do not contact with the sides of the trough and are 75 thereby protected from wear. These side walls 23 are provided with side apertures 29 to lighten the weight thereof and are also provided with end lugs 30 at one end adjacent the end of the next adjacent link thereby providing broad bearing surfaces 31 for the lugs which engage and hold the links when in vertical position as a stiff supporting member. This chain travels in an inclined trough 32 prior to entering the guide 20 beneath the 80 sprocket wheels 18 and 19. The forward end of the chain is connected to a special form of link formed like the other links save that it has an arm 33 extending at right angles to the fore and aft axis of the link. This arm is pivoted at 34 to the bottom of the dump body 85 35. The dump body itself is provided with side brackets 36 which are pivoted at 37 on the side frame members 1 and 2 in the usual manner. The usual tail gate 38 is provided 90 of any desired form or shape. 95

Method of operation

When the parts are as shown in Figs. 1, 2 and 4, the roller chain is resting in its guide- 100

way 32 with its forward end beneath the sprocket wheels 18 and 19 and its rollers resting on the arcuate guide face 21 of the guide 20. By the actuation of the handle 8 the power is applied through the shaft 7, gears 9 and 10, shaft 11, gears 12 and 13, and shaft 14 to the sprocket wheels 18 and 19. The teeth of the sprocket wheels engage with the exterior of the bearings 25 moving the chain 10 on its rollers along the guideway 32 and arcuate guiding surface 21 pushing the chain upwardly and in doing so the body 35 is pushed upwardly as the surfaces 31 engage each other forming a stiff body for thrusting the forward end of the dump body upwardly. Any tendency of the chain to sag and to become flexible again is resisted by the meeting of these faces 31 and the tendency of the chain is to move into such engaging position due to 20 the fact that as the body rises the pivotal point 34 travels backwardly with respect to the teeth of the sprocket wheels so that any sagging of the chain will cause the faces 31 to engage and the chain will remain a stiff member. The thrust upwardly is taken through the chain.

It will be understood that we desire to comprehend within our invention such modifications as may be necessary to adapt it to varying conditions and uses.

The block 20^a which rocks upon the top of the guide 20 forms a yielding chain guide. It is held in position by the side plates 20^b and the spring 20^c, which spring is maintained in position by the bracket 20^d.

Having thus fully described our invention, what we claim as new and desire to secure by Letters Patent, is:

1. In a dump body construction, an article 40 of manufacture for use as elevating means consisting of a linked body, each link consisting of a plate portion, side wall portions, arms projecting from the side wall portions into the next adjacent link between the next adjacent side walls, bearings on said arms, a shaft carried by said arms, a roller mounted on said shaft, said plate portions of the links being cut away to permit the roller to pass therethrough and extend therebeyond.

50 2. In a dump body construction, an article of manufacture for use as elevating means consisting of a linked body, each link consisting of a plate portion, side wall portions, arms projecting from the side wall portions into the next adjacent links between the next adjacent side walls, bearings on said arms, a shaft carried by said arms, a roller mounted on said shaft, said plate portions of the links being cut away to permit the roller to pass therethrough and extend therebeyond, said side wall member having engaging faces for preventing the chain so formed from flexing in one direction and with the other side wall portions cut away to permit the chain to flex 60 in the other direction.

3. In a dump body construction, an elevating means consisting of a member flexible in one direction and inflexible in the other, said member consisting of a series of links each of which consists of a plate portion, side wall portions, longitudinally extending spaced arms on the side wall portions projecting between the side wall portions of the next adjacent link, inwardly projecting bearing members on said arms, a shaft passing 70 through said bearing members and side walls of the next adjacent link for connecting the links one to another, and a roller on the shaft between the bearing members.

4. In a dump body construction, an elevating means consisting of a member flexible in one direction and inflexible in the other, said member consisting of a series of links each of which consists of a plate portion, side wall portions, longitudinally extending spaced 85 arms on the side wall portions projecting between the side wall portions of the next adjacent link, inwardly projecting bearing members on said arms, a shaft passing through said bearing members and side walls of the 90 next adjacent link for connecting the links one to another, and a roller on the shaft between the bearing members, said side walls having faces brought adjacent to one another for engagement to prevent the chain from 95 flexing in one direction and other portions cut away to permit it to flex in the other direction.

5. In a dump body construction, an elevating means consisting of a member flexible in 100 one direction and inflexible in the other, said member consisting of a series of links each of which consists of a plate portion, side wall portions, inwardly and forwardly extending arms on the side wall portions projecting between the side wall portions of the next adjacent link, bearing members on said arms and a shaft passing through said bearing members and side walls of the next adjacent link for connecting the links one to another, said side 105 walls having faces brought adjacent to one another for engagement to prevent the chain from flexing in one direction and other portions cut away to permit it to flex in the other direction and guiding projections on said 110 links for engaging with the guideways to prevent the lateral shifting of the links.

6. In a dump body construction, an article of manufacture for use as an elevating means 115 consisting of a linked body, each link consisting of a plate having on one end arms with bearings therein and on the other end sides with holes therein, a shaft passing through the bearings and holes on adjacent ends of two plates, and a roller on the shaft. 120

7. In a dump body construction, an article of manufacture for use as an elevating means 125 consisting of a linked body, each link comprising a plate having side walls, the side walls of each plate having holes in one of 130

their ends and the other ends extended and formed into round bearings adapted to fit between the side walls of an adjacent plate, a shaft adapted to extend through the bearings and the holes of the adjacent plate, and a roller on said shaft.

5 In testimony whereof, we affix our signatures.

RALPH E. SMITH.
